UNITED STATES PATENT OFFICE

2,460,623

LIQUID COOLER FOR AIR-CONDITIONING SYSTEMS

Mario Di Zoppola, New York, N. Y., assignor, by
mesne assignments, to Reconstruction Finance
Corporation, New York, N. Y., a corporation of
the United States

Application October 24, 1944, Serial No. 560,138

4 Claims. (Cl. 62—134)

1

This invention relates to a system for producing and regulating room temperatures and humidities and by means of which refrigerator and quick freeze units may be operated.

It is an object of this invention to provide a system of the character referred to above which lends itself to simplicity and compactness of construction so that it economically, efficiently and advantageously may be employed in a so-called small house as well as houses of larger room capacity.

Another object of the invention is to provide an ice creating and storage reservoir that may be incorporated into the system and which will so serve the air conditioning system that the refrigerant compressor system may be of a capacity to satisfy less than the peak load with the assurance, however, that the peak load, when it occurs, will be amply satisfied, the result of which will be that the installation and operational cost of the equipment may be comparatively low.

Another object of the invention lies in the construction and arrangement of several elements in such manner that the control of all of the operating units of the air conditioning, refrigerator and quick freeze units will be automatic and operable to produce variable temperatures and humidities when and where required.

It is a further object of the invention to provide such a novel and efficient ice creating and storage reservoir that the heat exchange will be rapid, with the result that the reservoir will be maintained, for all practical purposes, at the height of its supply efficiency.

Another object of the invention lies in so constructing a mechanism for controlling and circulating the heat transfer medium that it may be arranged in a self-contained unit of relatively simple and compact construction.

Other objects of the invention will appear as the description progresses, and it is thought unnecessary to here point them out in detail.

In the drawings I have illustrated and I will here describe a particular embodiment of my invention, but it is to be understood that many of the details of construction and of arrangement may be changed by those skilled in the art, and I therefore do not intend to be limited to those precise details except in so far as they are recited in the claims.

In the drawings:

Figure 1 is a diagrammatic view of a system embodying my invention;

2

Figure 2 is an elevation of the self contained unit for the circulating and control mechanism;

Figure 3 is an elevation looking at right angles to Figure 2;

Figure 4 is a horizontal sectional view on line 4—4 of Figure 2;

Figure 5 is a section on line 5—5 of Figure 4;

Figure 6 is a section on line 6—6 of Figure 2;

Figure 7 is a perspective view of one of the heat diffusers of the ice tank; and

Figures 8, 9 and 10 are diagrams of control circuits.

The illustrated embodiment of the invention includes an air conditioning unit A for heating and humidifying and for cooling and dehumidifying as required, a source B for raising the temperature of the heat transfer medium, a combined unit C for lowering the temperature of the heat transfer medium, after it has performed its transfer function, and for the creation of and storage of ice to supplement the compressor to satisfy the peak loads, a refrigerator D and a quick freeze unit E.

Referring now to Figure 1 of the drawings, and describing the interconnection of the units A, B, C, D and E, the unit B, which is in the form of a boiler whose construction will later be described, receives supply water from a valve controlled pipe 10 and is provided with an expansion tank 11. When the system is operating to heat and humidity, the water passes from the boiler through a pipe 12, a pipe 13 and a three-way valve 14 to a circulator 15, by which it is forced through a pipe 16 to and through the heat exchange coil 17. From this coil the water returns through a pipe 18, a three-way valve 18' and a pipe 19 to the unit B by way of the supply pipe 10, thus forming a closed system of heat transfer medium circulation.

In order that the room may be humidified a pipe 20 having a valve 21 therein is connected to the pipe 12 and to a pipe 22 which is also provided with a manual valve 23 and a solenoid valve 23' and terminates in a spray nozzle 24 within the unit A.

This pipe 20 may also extend, as indicated at 20', to the house plumbing for the supply of hot water.

The unit A, which includes a casing 24' in which the heat exchange coil 17 and the spray nozzle 24 are located, is provided at its inlet end with an air filter 25 and an impeller fan 26 which forces air through the casing 24' to the space to be heated and humidified, the air en-

training moisture from the nozzle 24, with the result that the temperature and humidity will be raised before the air reaches the space which is being heated and humidified.

I will describe the automatic control of this portion of the system later.

When the system is used to cool and dehumidify the space, the valves 14 and 18' will be operated to close the pipes 13 and 19 so that cold water from the storage unit C will pass through the pipe 27 to the circulator 15 by which it will be forced through the pipe 16, the heat exchange coil 17, the pipe 18, the three-way valve 18' and the pipe 28 to a spray distributor 29 within the storage unit C. This spray 29 will spray the water over the ice surrounding coils 30 through which circulates refrigerant gases with the result that the water returning through the pipe 28 will be chilled. The refrigerant coils 30 receive the refrigerant through pipes 31 and 33 from a compressor 32, returning the refrigerant gases to the compressor 32 through a pipe 34.

To operate the refrigerator D, the pipe 31 is connected with the pipe 36 which extends from the compressor 32 to refrigeration coils 38 and back to the compressor through a pipe 39, there being a solenoid valve 38' located in the pipe 36 between the compressor 32 and the refrigerator coils 38.

The quick freeze unit E which may, if desired, be constructed as an integral part of the refrigerating unit D, receives its refrigerant through a pipe 40, an expansion coil 41 and a pipe 42 in which system is interpolated a relatively smaller compressor 43.

The automatic control of the cooling and dehumidifying portion of the system, the refrigerator and the quick freeze units, will later be described.

It will be noted that the compressor 32 serves a dual function in that it operates in connection with the refrigerator unit D and with the expansion coils 30 which in turn cooperate with the heat exchange coils 17 during cooling and dehumidifying.

The interpolating of the ice storage tank C which automatically is kept up to sufficient capacity to meet the peak load, makes it possible to use a relatively small compressor at 32, and thus to effectuate an economy of installation and operation.

Describing now the construction and arrangement of the air conditioning unit A, the boiler B, the ice storage tank C and the compressors 32 and 43, it will be seen by reference to the drawings that they are located within a housing 44 to which the air inlet 45, and from which the air outlet 46, extend. This arrangement of the operating mechanism for heating and cooling the heat transfer medium within a single unit makes it possible economically to construct and install, both from the point of expense and space consumption, a system of the character hereinbefore described in houses of low cost.

The boiler B is of the fire tube type and includes an oil burner 47 of any desired construction, a combustion chamber 47', from which the hot gases pass through the heating tubes 48, and finally to a stack 49. The water surrounding the tubes 48 which enters the boiler through the pipe 10, is heated and passes on through the system when it is used for heating and humidifying, and to the house hot water supply, in the manner which has already been described.

The air conditioning unit A is preferably arranged so that it is located within the housing of the complete unit. The casing 24' of the air conditioning unit A is provided with a waste water drain 50 which will carry away the surplus water from the spray 24 when the humidifying portion of the system is operating and the water of condensation from the coil 17 when the dehumidifying system is operating.

The ice storage tank C is located preferably below the units A and B, while the compressors and operating apparatus thereof are located in a separate compartment within the housing of the complete unit.

15 The ice producing and storage tank C in the form illustrated includes a casing 51 that is provided with an insulated wall 52 and with a chamber 53 which is closed by an insulated cover 54. In this tank the ice is produced and stored and 20 the cooling fluid for the air conditioner is reduced in temperature.

A frame 54' is mounted in the chamber 53 and is adapted to support the cooling unit. This cooling unit is preferably of the form illustrated 25 in the drawing wherein there are a plurality of spaced plates 55. These plates 55 are made of two sheets of metal, between which refrigerant gas coils 30 are arranged. The inlet end of each coil is connected to a header 58 and the outlet 30 end to a header 59, the inlet header 58 being connected to the pipe 33 and being provided with an expansion valve 57, and the outlet header being connected to the pipe 34 as shown in Figure 1 of the drawing diagrammatically and 35 in Figure 5.

The plates 55 are loosely supported at their upper portions by links 60 on the frame 54' so that they may have free movement. To the lower ends of the plates springs 61 are attached, 40 which springs are also attached to the frame 54' as shown. These springs, in cooperation with the links, hold the refrigerant unit in a suspended and yet relatively stable position within the frame which, however, will be such as to permit movement of the unit under the influence of the formed ice, it being understood that the connection of the headers 58 and 59 is sufficiently flexible to permit such movement.

I have arranged a plurality of heat diffusers 50 62 between the plates and from the outside plates approximately one-half way to the wall of the casing 51. Each of these diffusers is loosely suspended from the plates by brackets 63 for example, and extends throughout the vertical extent of the plates. Each diffuser between the pairs of plates is provided with flanges 64 which are arranged to contact the plates while the diffusers between the outside plates and the wall of the casing are each provided with one similar bracket to engage the adjacent plate, and each diffuser is provided with louvres 65 to permit water circulation.

Thus when the chamber 53 contains water or other fluid of the desirable character, the refrigerant gas passing through the coils 30 lowers the temperature of the water to its freezing point through heat transfer through the plates 55. As the formation of ice on the surfaces of the plates 65 will act as an insulation (since ice is a poor heat conductor) the diffusers act to diffuse the heat throughout the water that lies between the plates and between the plates and the wall of the tank, with the result that a solid mass of ice will form around the refrigerant unit. Thus the ice will 70 be available to receive the water from the spray.

head 29 to reduce its temperature before recirculation.

Of course it is necessary that a space exists within the casing 51 and between its wall and the formed ice to permit the cooling of the water from the spray head 29, and the recirculation of the water by means of the circulator 15. Thus to arrest the outward growth of the ice I have provided a temperature responsive device, such as a thermostat which is electrically connected with a solenoid valve 66 in the refrigerant gas supply pipe 33, to control the flow of such gas through the coils 30. This thermostat may be of the type that has a bulb 61 connected to a capillary tube extending from the water within the casing to the thermostat, and which is so set as to operate at a temperature slightly less than the freezing temperature of the fluid in the tank. Thus when the ice forms around the freezing unit and grows outwardly it will contact the bulb and through one capillary tube operate the thermostat and cause the latter to actuate the solenoid valve 66 to stop the flow of the refrigerant gas. And as the ice melts the ice will recede from the bulb and with the rise in temperature of the surrounding water the thermostat will again cause the solenoid valve 66 to open to reestablish flow of the refrigerant gas through the coils 30. Should, through freezing of water, expansion occur between the plates, they will be permitted to move by the mounting on the links 60 and the springs 61 which will again position the unit as the ice melts. Thus not only will there be space provided for the flow of water through the tank, but the possibility of pressure on the tank by the ice formation will be relieved.

Describing now the control systems which are shown in Figures 8, 9 and 10, and now referring particularly to Figure 8, which controls the fan, circulator and humidity, the system which includes the motor-driven circulator 15, the motor-driven fan 26 and the solenoid valve 23', also includes a thermostat T-1 for winter operation, a thermostat T-2 for summer operation and a humidostat H, together with a single pole, double throw switch S-2 and a relay R. The thermostats T-1, T-2 and the humidostat H will be located in a convenient location within the space that is to be conditioned, the thermostats being thrown into and out of the system selectively by the switch S-2 as heating or cooling are required and the circulator system controlled by the automatic operation of the relay R by the operation of either of the thermostats T-1 or T-2 that is thrown into the system, and the water spray for humidifying being controlled by the humidostat H. Another feature of this wiring is that the humidifying spray operated by the solenoid valve 23' can only function when the fan 26 is running; this to avoid unnecessary flow of water through the spray, should the humidostat H call for humidity when the fan is not in operation.

The system is also provided with a switch S-2-1 by means of which the fan may manually be controlled for continuous operation and for ventilation only, should the thermostats T-1 or T-2 be satisfied at that time. The wiring diagram shown in Figure 9 is for the controlling of the compressor units 32 and 43. The controls of the compressor unit 32 include thermostat T-1 (for the ice storage tank) and thermostat TR (for the refrigerator), a solenoid valve 66 controlling refrigerant line to the ice tank, and a solenoid valve 38' controlling the refrigerant

line to the refrigerator; the relays R are operated by either thermostat T-1 or thermostat TR and are meant to feed electric current to the compressor unit 32 when either or both these thermostats call for cooling. The thermostat TQF in the quick freeze compartment operates independently the condensing unit 53, only when said quick freeze calls for cooling.

The manually operated switches SW are used 10 when the condensing units 32 and 43 should need to be independently cut off for oiling or adjustments.

Referring now to the diagram of the oil burner control illustrated in Figure 10 of the drawing, 15 the motor of the oil burner 47 is interpolated in the electric circuit which includes an aquastat A-1 that is located in the boiler, a protectorelay PR, an ignition device I and an oil valve OV.

The above wiring diagrams are simply for illustrative purposes and it will be realized that many 20 changes in these diagrams may be made within the skill of the art.

It will be seen that I have provided a system 25 for heating and humidifying a room space and for cooling the same in which a common circulator is selectively used with both of the systems, and wherein is interpolated a boiler producing all the necessary hot water for the heat exchange coil 11 and for house hot water supply, an ice 30 producing and storage tank which will make possible the continuous flow of cold water during cooling operations and wherein ice is formed and stored to insure the satisfying of the peak cooling load and yet make it possible to use a relatively 35 small and economical compressor. Moreover I have so arranged the compressor that it may operate also for a food refrigerating unit. With this arrangement I have incorporated automatic 40 controls to which the various operating devices will be responsive.

What I claim is:

1. In an ice producing and storage device, a 45 tank, a plurality of refrigerant fluid circulating units adapted to receive refrigerant fluid, means for supporting said units within said tank for movement in all directions, said means including links for supporting the unit and resilient means tending to return the unit to a predetermined 50 position, whereby when ice is formed around the unit the latter will be permitted to move in any direction as expansion may occur.

2. In an ice producing and storage device a 55 tank, a frame mounted in said tank, spaced pairs of plates and refrigerant fluid coils arranged in each of said pairs of plates movably mounted on said frame, and heat diffuser plates mounted on said first mentioned plates and disposed between said spaced pairs thereof.

3. In an ice producing and storage device, a 60 tank, a frame mounted in said tank, spaced pairs of plates and refrigerant fluid coils arranged in each of said pairs of plates movably mounted on said frame, and heat diffuser plates mounted on 65 said first mentioned plates and disposed between said spaced pairs thereof and extending from the outermost plates toward and terminating in spaced relation to the walls of said tank.

4. In an ice producing and storage device, a 70 tank, a frame mounted in said tank, spaced pairs of plates and refrigerant fluid coils arranged in each of said pairs of plates movably mounted on said frame, and heat diffuser plates mounted on 75 said first-mentioned plates and disposed between

said spaced pairs thereof and extending from the outermost plates toward the walls of said tank.

MARIO DI ZOPPOLA.
